US00D865758S

(12) **United States Design Patent** (10) **Patent No.:** **US D865,758 S**
Choi et al. (45) **Date of Patent:** **** Nov. 5, 2019**

(54) **PORTABLE ELECTRONIC DEVICE**

- (71) Applicant: **Samsung Electronics Co., Ltd.**, Suwon-si (KR)
- (72) Inventors: **Kwangha Choi**, Seoul (KR); **Sanhui Oh**, Seoul (KR); **Yongseok Bang**, Yongin-si (KR); **Jaehyung Hong**, Seoul (KR)
- (73) Assignee: **SAMSUNG ELECTRONICS CO., LTD.**, Suwon-si (KR)
- (**) Term: **15 Years**
- (21) Appl. No.: **29/582,610**
- (22) Filed: **Oct. 28, 2016**

Primary Examiner — Barbara Fox*Assistant Examiner* — Kristin E Reed(74) *Attorney, Agent, or Firm* — McAndrews Held & Malloy, Ltd.(57) **CLAIM**

The ornamental design for a portable electronic device, as shown and described.

DESCRIPTION

FIG. 1 is a front perspective view of a portable electronic device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The dashed broken lines in the drawings depict portions of the portable electronic device that form no part of the claimed design.
